ELECTRICAL METRONOME

Robert D. Veech, 11 Yates Ave.,
Commack, N.Y. 11725

Filed Apr. 22, 1968, Ser. No. 11,565

Term of patent 14 years

Int. Cl. D10—05

U.S. Cl. D42—7

FIG. 4

FIG. 2

FIG. 1

FIG. 3

FIG. 5

FIG. 1 is a front elevational view of an electrical metronome showing my new design;
FIG. 2 is a top plan view;

FIG. 3 is a bottom plan view;

FIG. 4 is a left side elevational view; and

FIG. 5 is a rear elevational view with the metronome resting on its right side.

The perforated material extends throughout the entire cross lined area. The dominant features of the design lie in the solid lines of the drawings and the broken line showings in FIGS. 1 and 2 of the drawings represent control buttons, jack connections, or the like.

I claim:

The ornamental design for an electrical metronome, substantially as shown and described.
